ATTORNEY

UNITED STATES PATENT OFFICE

2,209,086

LIGHT ATTACHMENT FOR IRONS

Imogene Johnson, Tulsa, Okla.

Application August 21, 1939, Serial No. 291,150

1 Claim. (Cl. 240—2)

This invention relates to improvements in sad irons of the conventional electrically heated type.

A principal object of this invention is the provision of a novel form of hand grip for such irons having a light attachment integrally formed and streamlined into the hand grip for illuminating the work passing under the iron during pressing operations.

Another object is to provide a novel form of plug receptacle which is integrally formed in the handle for receiving the current connecting plug, and is streamlined into the body of the handle for improvement of its general appearance and character.

15 A further object resides in the novel form of switch member provided for switching the light attachment current on and off.

A general object is the provision of a novel form of streamlined handle which is pleasing and 20 artistic in appearance, and highly utilitarian in the inclusion therein of a work-illuminating light and plug receptacle which serve to eliminate the need for separate parts heretofore provided in electric irons.

25 Other useful objects and advantages will be apparent from the following detailed description in connection with the accompanying drawing which illustrates an operative embodiment of this invention.

30 In the drawing:

Fig. 1 is an exterior side view of the iron and hand grip structure of this invention.

Fig. 2 is a sectional side view of the hand grip structure showing the details of its internal 35 structure and the arrangement of parts therein, and

Fig. 3 is a detail showing the switch arrangement for the light attachment on the hand grip.

Referring to the drawing, the numeral 1 designates the base of the iron which is provided with usual electrical heating elements (not shown) which are connected to the usual contact posts 2, only one of which appears in the drawing, which extend upwardly and slightly rearwardly 40 from the upper surface of base 1, and are located toward the rear end of the base. A hand grip 3, generally streamlined in its contours, and approximating a downwardly turned U-shaped 45 member in its general outline, is attached to the upper surface of base 1. The legs of the U forming the front and rear posts, 4 and 5 respectively, by which the hand grip is attached to base 1. Hand grip 3 is preferably constructed 50 of some suitable non-heating material such as

one of the many commercial plastic compositions or wood.

The front leg 4 is thickened at its base, being rounded and streamlined into the grip portion proper of the hand grip, and is sloped generally 5 downwardly and forwardly toward the forward end of the iron. A hollow recess 6 is formed in the forward face of leg 4 for the reception of a small electric light bulb, similar in size to a flashlight bulb but adapted to operate with the 10 current normally employed with electric irons, which is threaded into a concave metal reflector 8 seated in recess 6. The recess 6 is so formed in the stock of the hand grip 3 and front leg 4 as to be smoothly streamlined therein, so 15 as not to form any abrupt and inartistic break in the curvature of the hand grip, and extends through the hand grip at an angle forwardly and downwardly toward the forward end of the iron, conforming in direction generally to the shape 20 and curvature of the front leg 4. By this arrangement, the light rays from bulb 7 are thrown forwardly and downwardly upon the work passing under the forward edge of the iron and serves to brightly illuminate same for the benefit of 25 the operator. A hollow passageway 9 extends rearwardly through the hand grip and communicates at its forward end with the rear end of recess 6. Passageway 9 follows generally the contour of the hand grip, turning downwardly and 30 rearwardly through rear leg 5 which is considerably thickened in its base portion to provide room for a hollow plug receptacle 10 in the rear portion thereof surrounding contact posts 2. The rear end of passageway 9 communicates with receptacle 10 at a point adjacent the point of attachment of contact posts 2 to the upper surface of base 1 of the iron. The plug receptacle 35 is so formed as to be fully streamlined within the rear portion of leg 5 of the hand grip and serves 40 to completely enclose the contact posts 2 and so present a distinctive and slight appearance to the eye. The usual current attachment plug 11, is shown in position in receptacle 10 in full outlines in Fig. 1, and in dotted outlines in Fig. 2. 45 Current leads 12 and 13 are laid in passageway 9 and at their rearward ends are connected to the respective contact posts 2. Lead 12 is connected at its forward end to the metal reflector 8, making electrical connection thereto. The 50 forward end of lead 13 is connected to a contact strip 14, consisting of a flat spring metal strip, which has one end rigidly connected to one side surface of recess 6 and extends transversely 55 across the recess and adjacent to the end of bulb 55

7 through the opposite side of recess 6 to the exterior of hand grip 3. A circular disc 15, dished in its center portion, is fastened to the outer end of strip 14 and forms a switch button 5 for the light and is so positioned, angularly, with respect to the hand grip, that it may be operated by depressing same by the thumb of the operator, which normally rests in close proximity to disc 15. By means of its resilient character, 10 contact strip 14 is arranged so that it is normally out of contact with the contact end of light bulb 7, so that under normal conditions no current will flow to the light bulb. When it is desired to turn on the light, the operator merely brings the 15 thumb of the hand operating the iron to rest upon disc 15, and by slight pressure thereon depresses contact strip 14 into contact with light bulb 7, causing same to light up. The position of disc 15 is such that the operation of turning the light 20 on and off may be effected without altering the normal position of the hand guiding the iron and without fatigue thereto even when necessary or desirable to hold the switch closed for considerable periods of time. If desired, contact 25 strip 14 can be made of sufficiently strong spring metal so as to resist the normal weight of the thumb resting thereon, but not sufficiently strong to prevent closing of switch by the exertion of slight extra pressure by the thumb. Thus, the 30 disc may serve both as a thumb support and as a switch for the light. By the described arrangement it will be seen that current required by the light bulb 7 is taken from the current being supplied to the heating elements of the iron in the 35 usual manner.

From the foregoing, it will be evident that this invention provides a novel form of hand grip for electric irons which is pleasing and artistic in appearance and provides a highly useful device for 40 illuminating work being pressed, and for avoiding the unsightly appearance of other construction.

tions caused by the normally exposed contact posts connected thereto.

What I claim and desire to secure by Letters Patent:

An electrically heated sad iron having in combination, a body portion having the usual contact posts for the heater coils extending upwardly from the rear portion thereof, a generally U-shaped handle downwardly turned and having the legs thereof attached to the upper surface 10 of said body portion, the rear one of said legs having a thickened base portion, an upwardly opening plug receptacle integrally formed in said thickened base portion of the rear leg and enclosing said contact posts, a recess integrally 15 formed in the front leg of said handle, said recess opening forwardly and downwardly toward the forward end of said iron, a bore extending through said handle connecting said plug receptacle with said recess, a light bulb and reflector positioned in said recess to direct the light rays from said bulb downwardly and forwardly of said iron, conductor leads extending through said bore and connecting said light bulb to said contact posts, and a thumb-operated 20 switch positioned in said recess and connected into the circuit to said light bulb, said switch comprising an elongated flat spring member extending transversely through said recess and normally out of contact with said light bulb, one end 25 of said spring member being fixedly attached to a side wall of said recess and connected to one of said conductor leads, the free end of said spring member protruding laterally outside said front leg, a disc member mounted on said free end 30 of the spring member and adapted to be depressed by the thumb of the operator to thereby force said spring member into circuit-closing contact with said light bulb.

40
